TEMPERATURE CHANGING SYSTEM FOR
TANKSCarl S. Brown, Lakewood, Ohio, assignor to
Glascote Products, Inc., Euclid, Ohio, a corpora-
tion of Ohio

Application January 20, 1939, Serial No. 251,951

8 Claims. (Cl. 257—189)

This invention relates to an improved temperature changing system of tanks, and especially to a system wherein a liquid medium is applied in a film to the wall of the tank to obtain the desired temperature change in the contents of the tank. This, therefore, is the general object of the present invention.

A more specific object of this invention is to provide a temperature changing system for tanks, wherein a cooling or heating fluid is directed from a suitable supply through a plurality of orifices to the side walls of a tank, in such a manner as to substantially envelop the side wall of the tank with a thin flowing film of fluid, and wherein the arrangement is such that clogging of the orifices is minimized and for all practical purposes eliminated, thus enabling the assembly of the tank and temperature changing system of a single permanent unit, and avoiding the need for removal of the system for cleansing purposes.

A further object of this invention is to provide a cooling system for tanks, wherein the tank and its contents may be heated by a heating medium, such as steam, and then quickly cooled by the application of a thin film of cooling liquid to the walls of the tank.

Other objects and advantages of this invention will become more apparent from the following description, reference being had to the accompanying drawing, wherein a preferred embodiment of the invention is illustrated, in the form of a jacketed tank, the jacket itself carrying the channel for the fluid. This is one of the features of my invention.

In the drawing, Fig. 1 is a side elevation of an apparatus, illustrating my improved system; certain portions of the apparatus being broken away to more clearly illustrate the internal construction thereof; Fig. 2 is a fragmentary horizontal section, the plane of the section being indicated by the lines 2—2 of Fig. 1.

In the drawing, I have illustrated a tank 10, the contents of which are to be cooled or heated. The tank is supplied with suitable inlet and outlet openings, one of which is generally indicated at 11. As illustrated, the tank 10 comprises a metallic enclosed body, formed in any well known manner, as for instance, by welding. However, my improved apparatus will operate well with a non-metallic or coated metal tank. The temperature change is accomplished by enveloping the external side wall of the tank 10 with a thin running film of cooling or heating fluid. To this end the tank 10 is preferably enclosed by a

jacket or second tank 20, which, when steam is used as a heating medium, provides a steam jacket. This jacket is spaced from the side and bottom walls of the tank 10, and may be provided with suitable supports 21. The upper edge of the jacket 20 extends substantially to the plane of the head of the tank 10, and an annular closure plate 22, which is substantially flush with the top of the tank 10, bridges the gap between the jacket and the tank 10.

The jacket 20 is provided, adjacent its upper end, with an inlet opening 23, and an internally threaded flange member 24, to enable the piping of a fluid direct to the interior of the jacket. Secured to the inner surface of the side wall of the jacket 20, adjacent its upper end, is an angle member 25 formed in a continuous annulus, the horizontal flange thereof being welded, as at 26, to the inner surface of the jacket 20, a slight distance below the bottom of the inlet opening 23. The vertical flange 27 of the angle 25 extends upwardly and is spaced a small distance from the exterior wall of the tank 10. This provides a channel 28 to receive the fluid from the inlet 23, and distributes such fluid around the periphery 25 of the jacket.

The fluid flows from the channel onto the tank 10 through a series of equi-spaced vertically extending slots 29, formed in the vertical flange 27 of the angle 25. It will be noted that the walls 30, 31, which form the lowermost boundaries of the slots 29, are in a plane above the upper surface of the horizontally extending portion of the angle 25, as well as above the upper surface of the inlet opening 23. Thus, a trap is formed, which collects the sediment in the fluid and aids materially in maintaining the slots or orifices 29 open.

A guard plate or baffle member is interposed between the jacket inlet and the adjacent orifices 29, and serves to prevent direct flow through such orifices, thus causing the fluid medium to be substantially evenly distributed around the jacket channel 28, an even film thereof enveloping the tank 10. This baffle member is shown in Fig. 1 at 31, as being welded to the closure plate 22 and extending downwardly to a point below the lowermost plane of the slots 29 and circumferentially a distance sufficient to divert the flow of fluid medium, as indicated in Fig. 2.

The jacket 20 is provided with a suitable valved drain, generally indicated at 33, as well as with an overflow drain 34. The latter retains the liquid in the jacket below a comparatively low maximum height. The drain 34 is best shown in Fig. 1, and comprises a liquid trap 55

- which not only limits the upper liquid level in the jacket, but also provides a liquid seal which prevents the setting up of air currents within the jacket, which might affect the distribution 5 of the film of fluid medium applied to the tank 10.
- When steam is used as a heating fluid, the drain 34 serves as a steam trap. The water in the trap below the outlet then determines the maximum steam pressure in the space between 10 the jacket and the tank. Sometimes it is desirable to raise the temperature of the contents of the tank with steam and then quickly cool the same. With my improved tempering system, the cooling fluid may be admitted to the channel 28 15 before the steam has become entirely exhausted from the jacket, and as the arrangement is such as to deliver a thin film of cooling fluid to the exterior of the tank, cooling commences immediately.
- With certain fluids it has been found desirable 20 to obstruct the flow of the fluid in the channel 28 to insure an even distribution of the fluid around the periphery of the tank 10 in all regions, especially those regions lying adjacent to the inlet opening 23. To this end I prefer to use a pair 25 of vertically extending V-shaped members or dams, one of which is shown at 40 on Fig. 2, and the other of which is similarly spaced on the other side of the axis of the opening 23.
- These plate members may be secured to the bottom wall of the angle 25 by welding or any other well known method, and are preferably about 30 half the height of the vertical extent 27 of the angle 25.
- From the foregoing it will be seen that I have 35 provided a temperature changing system for tanks, which will efficiently distribute a fluid to a tank through a plurality of orifices in a channel which may be carried by a jacket, between the jacket and the tank, and I have so arranged 40 the channel and the orifices therein as to prevent clogging of the orifices for all practical purposes.
- I claim:
1. The combination of a tank, a channel surrounding the tank and having a substantially horizontal base and a pair of vertically extending walls, one of said walls being parallel with and spaced from the wall of the tank, and having a series of vertical slots extending downward from the top of the wall to points spaced above the horizontal wall, and an inlet passageway communicating with said channel, said passageway being spaced above the bottom wall of said channel, and a baffle member interposed between said 55 passageway and the slots.
  2. The combination of a jacketed cylindrical tank, an annular channel provided by an angle member formed into an annular ring, said member having a horizontal flange welded to the interior wall of the jacket adjacent its upper end, and a vertical flange extending upward from the horizontal flange adjacent to but spaced from the tank, said vertical flange having a series of vertical slots extending downward from the top 60 of said flange to points spaced above the horizontal wall of said channel, said jacket having an inlet opening spaced above the bottom wall of said channel, but below the bottom of the slots therein, and a baffle member interposed between the inlet opening and the slots and spaced from the bottom wall of said channel.
  3. The combination of a jacketed tank, a channel carried by said jacketed tank intermediate the jacket and the tank and having a substantially horizontal base and a pair of vertically ex-

tending walls, one of said walls being parallel with and spaced from the wall of the tank, and having a series of vertical slots extending downward from the top of the wall to points spaced above the horizontal wall, and an inlet passageway through said jacket and communicating with said channel, a baffle member interposed between said passageway and the slots and spaced from the bottom wall of said channel, and means in said channel adjacent opposite ends of said baffle to partially dam the flow of liquid in the channel.

4. A temperature changing system for a vertical jacketed tank, comprising an open top horizontal channel made by an annular angle bar 15 carried by the jacket between the tank and the jacket, and having a horizontal flange attached to the jacket and a free vertical flange, said channel being spaced from the tank and provided with a plurality of openings through its 20 vertical flange, whereby a liquid cooling or heating medium may flow through said openings and impinge directly on the exterior of the tank and flow downwardly in a thin film along the wall of the tank.

5. A temperature changing system for a jacketed tank, comprising a channel carried by the jacket between the tank and the jacket, said channel having an inner upright wall with a plurality of slots leading downwardly and terminating above the bottom of the wall, whereby a liquid cooling or heating medium may flow through said slots and impinge on the exterior of the tank, and wherein the channel is deeper than the slots, whereby sediment may collect in said 35 channel without obstructing the slots therein.

6. The combination of a jacketed cylindrical tank, an annular channel provided by an angle member formed into an annular ring, said member having a horizontal flange welded to the interior wall of the jacket adjacent its upper end, and a vertical flange extending upward from the horizontal flange adjacent to but spaced from the tank, said vertical flange having a series of vertical slots extending downwardly from its upper edge.

7. In a temperature changing system for tanks, an open top conduit surrounding the tank adjacent the top thereof and having a side wall spaced from and substantially parallel with the 50 wall of the tank, means to conduct liquid to said conduit, said conduit side wall having a plurality of horizontally spaced vertically extending elongated slots, each slot extending upward from a point adjacent the bottom of the conduit toward the top of said conduit wall.

8. In a temperature changing system for vertical walled tanks, a channel open at its top surrounding the tank adjacent the top thereof and having a side wall spaced from and substantially parallel with the wall of the tank, means to conduct liquid to said channel, said channel side wall having a plurality of horizontally spaced vertically extending elongated slots, each slot extending upward from a point adjacent the bottom of the channel to the extreme top of said channel wall, whereby a clogging of the lower portions of the slots due to a collecting of sediment in the bottom of the channel will be compensated for by an attendant rise in the liquid level in the channel, and due to the elongation of the slots the volume of liquid passing therethrough to the wall of the tank will remain unaltered.
